SAFETY DEVICE FOR ELECTRICAL HEATING APPARATUS

Filed Jan. 18, 1927

Inventor:
Patrick McIlvenny
By Arthur M. Clegg

UNITED STATES PATENT OFFICE.

PATRICK McILVENEY, OF AUCKLAND, NEW ZEALAND.

SAFETY DEVICE FOR ELECTRICAL HEATING APPARATUS.

Application filed January 18, 1927, Serial No. 161,944, and in New Zealand December 14, 1926.

My invention relates to safety devices for electrical heating apparatus which are employed for the purpose of automatically breaking the circuit through the heating elements thereof when the apparatus becomes heated beyond a pre-determined or required degree of temperature, and relates particularly to that class of safety devices in which, upon the apparatus becoming heated to excess, a fusible metal or alloy is fused and the heating circuit thereby broken.

According to the present invention, the circuit is normally retained closed by means of a contact-making member adapted to bridge contacts in the heating circuit, such contact-making member, notwithstanding the tension of spring means in the opposite direction, is held in such bridging position by a retaining piece adhered to a portion of the apparatus by a fusible adhering medium, such as solder, the arrangement being such that when the metal is fused by excessive heat, the contact-making member will, under influence of the spring means, be actuated to break the contacts, and the heating circuit will thereby be opened and no further heat will be generated until the contacts are again bridged upon the replacement of a retaining piece.

Approved forms of carrying out the invention will now be described in detail with reference to the accompanying drawings, wherein:—

Figure 1, is a cross section through an electric laundry iron showing the invention applied thereto.

Figure 2, is a plan showing the contacts in the iron to which the heating elements are connected.

Figure 3, is a cross sectional elevation through the retaining piece and a guiding tube.

Figure 4, is a plan of the top of the tube.

Figure 5, is an elevation showing the top portion of the tube.

Figure 6, is an inverted plan of the top of the tube.

Figure 7, is a sectional elevation of a bridging piece and associated parts.

Figure 8, is an inverted plan of the bridging piece.

Figure 9, is a cross sectional elevation showing an alternative method of bridging the contacts.

Figure 10, is a cross sectional elevation showing a slightly modified guide.

According to the drawings, but more particularly to Figures 1 to 8, a rod 1 is guided in a guiding tube 2, fixed in a convenient portion of the heating apparatus; in Figure 1 it is shown screwed into the cover 3 of an electric iron. The lower end of the rod 1 contains a circular bridging piece 4 insulated therefrom and bridging the contacts 5 and 6 which are arranged in the circuit of the heating elements. The bridging piece 4 is normally held against the contacts 5 and 6 by a retaining plate 8 adhered to the top of the tube 2 by a layer of fusible metal 9, such as solder. A spring 10 is fixed at one end to any suitable position of the heating apparatus; in Figure 1 it is shown passing beneath the handle support 11 of the iron, and has its other end passing through a slot 12 in the tube 2 and through an opening 13 in the rod 1, so that when the plate 8 is freed from the top of the tube by the melting of the metal layer 9, the rod will be carried upwards by the spring 10 and the bridging piece 4 will break the contact between the contacts 5 and 6, thus breaking the circuit of the heating elements.

For convenience in again bridging the contacts 5 and 6, the plate 8 is preferably adhered by the metal layer 9 to another plate 14, having a hole through which the upper end of the rod passes, the plate 8, fusible layer 9 and the plate 14 forming a removable cap for the tube 2. This plate 14 contains hooks 15 adapted to engage beneath the flange 16 projecting outwardly from the top edge of the tube. When placing a cap in position the hooks 15 are inserted through the gaps 17 and rotated beneath the flange 16, which is tapped as at 36 to facilitate the hooks 15 passing thereon. If desired, a pin 18 projecting from the underside of the flange will prevent the cap being rotated completely around the flange and so prevent the hooks 15 again entering the gaps 17. The top of the plate 8 is formed with a recess 37 to receive the upper end of the rod which is of such a length that the end thereof must project through the plate 14 before the cap can be placed on the tube 2. Thus, when the metal 9 is once fused, a fresh cap is replaced upon the tube. Another form of cap would be as shown in Figure 10, where the bottom end

of the tube 2^a is shown screwed into a plug 19 also screwed into a wall 20 of the apparatus. In this case, when rebridging the contacts, a fresh cap comprising the parts 8, 5, 9 and 2^a, is screwed into the plug 19.

The bridging piece 4 (see Figures 7 and 8) is attached to the lower end of the rod 1 as follows:—

A metal disc 22 bears against a shoulder 10 formed at the end of the rod 1, and on the underside of this plate a disc 23 of insulating material, such as mica, is placed, and then upon this a disc 24, having a projecting flange forming the circular bridging piece 15 4, is placed. An opening 25 in the disc 24 is sufficiently large to ensure that it will not come in contact with the rod 1. Below the disc 24 another disc 26 of insulating material, such as mica, is placed, and then a metal 20 washer 27 over which the end of the rod 1 is riveted.

In Figure 9, an alternate form of bridging piece is shown, and consists of an arm 29 pivoted in a bracket 30 fixed to a convenient part 25 of the apparatus, in this instance, to the weight block 31 of the iron. At its contact end the arm carries a separate metal contact plate 32 insulated by insulating material 33 from the arm 29. The contact rod 1 in this 30 case is not fixed to the bridging piece but merely rides upon the arm 29 and may have its lower end slightly pointed and riding in a slight depression 34 in the top of the arm as shown. The spring 10 in this case has its end 35 carried down through an opening 35 in the cover and passes through an eye 36 on the top of the arm 29. When the plate 8 parts from the plate 14, or from the tube 2^a as the case may be, the spring 10 will, through the intervention of the arm 29, break the connection 40 between the contacts 5 and 6.

The contacts 5 and 6 are formed from spring leaves and are insulated from the metal weight block 31 by a sheet 38 of insulating material, such as mica, and immediately below them a depression 39 is provided. This depression ensures that a certain amount of flexibility is given to the contacts which will enable better contact to be 50 made by the bridging piece, and to allow for any expansion of the parts.

In Figure 9, it will be noticed that the ends 5 and 6 of the contact pieces are turned upwards, this being merely for the purpose of 55 making more suitable contact for the bridging piece 32.

No part of the device, except the actual bridging piece, at any time comes into contact with the circuit, and thus there is no danger 60 of a short circuit from the heating circuit passing through any of the other parts of the device.

What I claim is:—

1. In safety devices for electrical heating 65 apparatus of the kind referred to, a contact-

making member adapted to bridge contacts of the heating circuit, a readily detachably and renewable portion upon the apparatus affected by the heat thereof, a retaining-piece adhered to said detachable portion by a fusible adhering substance such retaining-piece holding such contact-making member in bridging position against the contacts and retaining the circuit closed, and a spring adapted to break such bridging by actuating such contact-making member when the retaining-piece is released on the fusing of the said substance. 70

2. In electrical heating apparatus, contacts of the heating circuit, a bridging piece adapted to bridge said contacts, a readily detachably and renewable portion upon the apparatus affected by the heat thereof, a retaining plate adhered by fusible metal to said detachable portion, a rod interposed between such bridging piece and the retaining plate whereby said bridging piece is retained against the contacts, a spring operable upon said bridging piece and rod whereby when the retaining plate is released by the fusing of the fusible metal the bridging piece will move away from the contacts and break the heating circuit. 80

3. In the device as claimed in claim 2, said spring in the form of a leaf spring attached at 85 one end to a wall of the apparatus, a tubular guide through which said rod passes, a slot in said tubular guide, the other end of said spring passing through said slot and through a hole in said rod. 100

4. In the device as claimed in claim 2, a tubular guide through which said rod passes, a flange projecting outwardly from the upper end of said guide tube, a plate to which said retaining plate is adhered, and hooks upon 105 said plate adapted to engage beneath said flange.

5. An improved safety device for electrical heating apparatus comprising in combination a guiding tube, a retaining plate attached to the top of said guiding tube by a layer of fusible material, a contact bridging piece, a rod arranged in said tube and adapted to close a circuit by means of said contact bridging piece, and a spring whereby said rod is held in the circuit closing position by the retaining plate against the tension of said spring. 110

6. An improved safety device for electrical heating apparatus comprising a tubular guide fixed at one end to a wall of the heating apparatus, a retaining-plate adhered by fusible material to the other end of said guide affected by the heat of said apparatus, a contact bridging member adapted to bridge contacts, a rod arranged in said tube and adapted to close the circuit by means of said contact bridging piece and fixed to said contact bridging piece but insulated therefrom, a spring fixed to a part of the apparatus engag- 115 120 125 130

ing said rod whereby said rod is held in circuit closing position by said retaining plate against the tension of said spring.

7. An improved safety device for electrical heating apparatus comprising a guiding tube, a separate portion detachable from the upper part of said tube, a retaining plate attached to the said separate portion by a layer of fusible material, a contact bridging piece, 10, a rod arranged in said tube and bearing

against said retaining plate and adapted to close the circuit by means of said contact bridging piece, and a spring whereby said rod is held in the circuit closing position by the retaining plate against the tension of said 15 spring.

In testimony whereof, I have signed my name to this specification.

PATRICK McILVENEY.
